UNITED STATES PATENT OFFICE

HARRY S. HART, OF CHICAGO, ILLINOIS, ASSIGNOR TO RODGER BALLAST CAR COMPANY, OF CHICAGO, ILLINOIS, A CORPORATION OF MAINE

CONTROL MECHANISM FOR HOPPER CAR DOORS

Application filed November 7, 1931. Serial No. 573,573.

This invention relates to a new and improved control mechanism for the doors of railway hopper cars and is particularly designed for the inner doors of hopper cars having longitudinally disposed V-shaped hoppers on opposite sides of the center sill, each provided with a pair of discharge doors pivoted on an axis located at the apex of the "V" defining the contour of the hoppers.

It is an object of the present invention to provide operating and control mechanism for the inner hopper doors of a car of the above described type, which is positive in both the opening and closing movements, whereby the control mechanism will impart a positive opening movement without reliance upon the force of gravitation exerted by the lading carried in the car.

Control mechanisms heretofore employed for this use have had a positive, moving force exerted in the closing direction only, and have relied on the weight of the lading in the car for effecting the opening movement of the door. This type of mechanism has been found imperfect in performance due to the fact that the doors in some instances become stuck so that they will not move automatically in the opening direction under the gravitational force of the lading when the operating means is released.

It is accordingly another object of this invention to provide a door operating means, the use of which will eliminate any sticking of the door in the objectionable manner above referred to.

It is a further object of this invention to provide a door operating mechanism which is simple in construction and yet positive and efficient in operation and which may be actuated by means readily accessible to the operator for quick and positive discharge of the lading of the car.

It is a further object of this invention to provide a mechanism which is adapted for installation in the limited space provided therefor in cars of standard construction and which is adapted for combination with the structural parts now constituting the standard A. R. A. car under structures.

These and other objects not specifically

enumerated, will readily appear to one skilled in the art as the following description proceeds.

The present disclosure is merely given by way of example and should not be considered as limiting the invention in any respect as the scope of the invention should be determined from the appended claims and an appreciation of the advantages which the invention produces in the disclosed embodiment.

The following description may be more readily understood by referring to the accompanying drawings in which:

Figure 1 is a side elevational view of a railway car constructed with longitudinal V-shaped hoppers on each side of the center sill and equipped with door control mechanism constructed in accordance with this invention;

Figure 2 is a cross sectional view of the car shown in Figure 1;

Figure 3 is an enlarged detailed view, partly in cross section, showing a fragment of the car and the door control mechanism as seen from the side;

Figure 4 is an enlarged transverse view, partly in cross section, disclosing the car center sill, the inner hopper doors in closed position, and the door operating mechanism therefor, and

Figure 5 is a view similar to Figure 4, with the doors in open position.

By referring to the drawings, it will be noted that the present invention is disclosed as applied to a hopper car 10, having the usual under structure 11 and body 12, provided with a center sill 13. The bottom of the car body is provided with sloping floors or shedding surfaces 14 and 15 which form with the outer hopper doors 16 and inner hopper doors 17, a pair of longitudinally disposed V-shaped hoppers on opposite sides of the center sills. The inner and outer doors of each hopper are mounted for pivotal movement on axes 18 located at the apex of the "V" defining the contour of the hoppers so that the doors move downwardly in opening for discharge of the lading. In cars of this character, it is custom-

ary to provide separate door control means for the inside hopper doors and the outside hopper doors, and no change is made in this customary arrangement by the present invention.

Accordingly, it is to be understood that the outside doors are provided with suitable operating mechanism of any usual satisfactory construction so that they may be opened and closed in the customary manner. It is also usual in this type of car to provide door control mechanism for the inner doors of a type that actuates both doors simultaneously.

It is the mechanism which is employed for operating the inner doors that constitutes the subject matter of this invention. The control mechanism of this invention comprises a long shaft 20, disposed below the center sills and mounted for rotation in brackets 21 and 22 secured to the under side of the center sill. There are preferably two such shafts similarly mounted for the entire car, each shaft extending the length of the two co-extensive hoppers located throughout one-half the length of the car.

In the present disclosure, each of the inside doors is provided with duplicate mechanisms attached to the doors at the opposite ends. By referring to Figures 3, 4 and 5, of the drawings, it will be noted that hubs 23 and 24 are provided fixed to the shaft 20 and disposed on opposite sides of bracket 22. Each of these hubs is provided with a pair of spaced, radial ears 25, having bearing openings in the end thereof for pivots 26. The hubs are disposed on the shaft so that the ears of the hub 23 are at a 90 degree angle to the ears of the hub 24, and also, in such manner that the ears will be positioned upwardly as shown in Figure 4, when the doors are in closed position.

Mounted on the pivot 26 carried by each lug, is a hook shaped link 27, carrying a bearing pin 28, in the lower end thereof. This bearing pin 28 is pivotally connected to the intermediate portion of a lever 30, pivoted at its upper end in a bearing 31, carried in the lower portion of bracket 22. It will be noted that the bearing 31 lies immediately below the shaft 20.

On the under side of each of the inside doors, a bracket 32 is provided having an elongated slot 33 therein adapted to receive the pin 34, carried in the outer end of the lever 30. A lever 30 and the door 17 are so arranged as to constitute a pair of slidably connected toggle links so that when the toggle mechanism is disposed in the maximum upper position the door is closed and when disposed in a maximum lower position, the door is open.

In view of the fact that the opposite doors are actuated by hubs 23 and 24, axially displaced on the same shaft, it is necessary to project the edge of one of the doors in a

direction longitudinally of the car beyond the point necessary for merely closing the hopper opening. This is clearly shown by comparing Figures 3 and 5, where in Figure 3, the door 17, on the left hand side of the car is shown projected as at 17' in a manner to position the slide 32 carried by the edge of the door, in close proximity to the links 30 and 27 disposed to the left hand side bracket 22. On the other hand, the door of the right hand hopper is actuated by means of the hub 23 and links on the right hand side of the bracket 22 whereby the edge of the door may be terminated to position the slide bracket 32 closer to the hopper opening.

The extended hopper may be determined from Figure 3, where the end wall 40 and sloping floor 41 are shown. The end wall serves to close the end of the hopper whereas the doors are each provided with an upstanding extension 42, moving with the door to form an extension of the end wall 40 for guiding the lading during discharge. It is preferable to construct the door on one side of the car with an extension at one end, but to provide the extension at the opposite end on the opposite door, whereby a symmetrical but reversed installation is provided.

An important factor of this mechanism is that the pivot 31, carried by the bracket 32, is so disposed with respect to the door and the actuating mechanism, that the link 30 is disposed at substantially right angles to the plane of the door when the door is closed, whereby the door is effectively locked in closed position by a positive prop which serves to support the load of lading resting on the door.

Another important feature resides in the construction of the hook-shaped link 27, whereby the end bearings or pivots thereof will be disposed at diametrically opposite points of the hubs 23 and 24 and in a straight line with the center of the shaft 20, when the door is in closed position. This arrangement is clearly shown in Figure 4, where it will be observed that any force in an opening direction exerted on the lower end of the hook-shaped link 27 will be resisted by the aligned disposition of the link bearings on opposite sides of the center of the shaft. In this manner the actuating mechanism is effectively held and locked when the door is in closed position, whereby the link 30 is positively held against movement and being so held, forms a positive direct prop, in engagement with the outer end of the door itself. Any suitable means may be employed for imparting a rotary movement to the shaft 20, but it is preferable to provide a worm gear 50, fixed to the shaft and disposed for engagement with the worm 51 mounted on the transverse shaft 52.

The transverse shaft preferably extends in

opposite directions from the center, to a position adjacent the sides of the car with suitable construction in the ends for imparting rotary movement by manual operation. This may be done by a crank, lever or other conventional mechanism now used for this purpose, preferably duplicated at both sides, whereby the inner doors may be operated from either side of the car.

In operation, the inner doors at the opposite sides of the car, are operated simultaneously by merely operating the shaft 52 from either side of the car. Upon rotation in the proper direction, a rotary movement is imparted to the shaft 20, through the worm and worm gear 51 and 50 respectively, all in a manner to give rotation to the shaft 20 in a counter-clockwise direction, as shown in Figure 4.

The initial movement of the shaft 20 serves to unseat the hook links from their hanging locked engagement with the hubs and to immediately cause rotation of the links 30 in the downward direction. The links 30 have a sliding engagement with the doors whereby the doors are likewise started in a downward direction. It will be observed that this action is positive and inescapable upon movement of the shaft so as to overcome any tendency for the doors to stick or otherwise remain in closed position. Obviously, the continued movement of the parts causes the doors to continue their opening movement until they assume the maximum open position such as shown in Figure 5, when the pivots 34 in the ends of the links 30 have reached the extreme outer position of the elongated slots 33.

In open position, the links 30 are located in substantially the position of the tangent to the arc of swing of the door which passing through the pivot 31, so that the load of the door in this position and the discharging lading thereon is supported with a maximum efficiency.

It is observed that the reverse rotation of the shaft will serve to move the link mechanism upwardly with a corresponding movement of the door until the link 30 approaches the maximum upper position where it is gradually wedged into a locking, propping position with the end of the door.

The mechanical advantage effected by this arrangement is very great, so that there is very little tendency for the links 30 to become displaced from their propping positions with the doors. Consequently, there is very little load placed on the links 27 when the door is in closed position.

Furthermore, although the load on the links 27 is only a slight one, they are so constructed that their pivots are disposed in alignment with the center of the shaft 20 and on opposite sides thereof whereby the link

30 is directly supported by the shaft 20 and locked against accidental movement.

The door mechanism of this invention not only provides for positive actuation in both directions of movement, but also provides means for maximum efficiency in supporting the door in closed position free from liability of becoming disengaged under the load of the supported lading.

I claim:

1. In combination with a hopper car having a longitudinal V-shaped hopper on one side of the center sill and an inner door therefor pivoted at its bottom edge at the apex of the hopper, control means therefor comprising a link mounted for pivotal movement at substantially the center line of said car and in substantially the horizontal plane of the hinge of said door, said link having a sliding connection at its outer end with said door and means for oscillating said link for opening and closing said door.

2. In combination with a hopper car having a longitudinal V-shaped hopper on one side of the center sill and an inner door therefor hinged at its lower edge at the apex of said hopper, control means therefor comprising a link pivoted below the center sill of said car having sliding connection with said door means for moving said link for opening and closing said door, said link being constructed and arranged to approach a position perpendicular to the plane of said door in movement through the final closing positions whereby said link forms a wedged support for said door in closed position.

3. In combination with a hopper car having a longitudinally disposed V-shaped hopper to one side of the center sill and an inner door therefor hinged at its lower edge to the apex of said hopper, control means therefor comprising links pivotally mounted centrally of the car having sliding connections with said door for imparting opening and closing movement thereto said links and door constituting slidably connected toggles constructed and arranged so that said links assume positions substantially perpendicular to said door in the extreme open and closed positions whereby said links form strap supports for said door in open position and wedging props for the outer edge of said door in closed position, and means for imparting opening and closing movement to said links.

4. In combination with a hopper car having a longitudinally disposed V-shaped hopper to one side of the center sill and an inner door therefor hinged at its lower edge to the apex of said hopper, control means therefor comprising links pivotally mounted centrally of the car having sliding connections with said door for imparting opening and closing movement thereto, said links and door constituting slidably connected toggles constructed and arranged so that said links as-

sume positions substantially perpendicular to said door in the extreme open and closed positions whereby said links form strap supports for said door in open position and wedging props for the outer edge of said door in closed position, and means for imparting opening and closing movement to said links, comprising a longitudinal shaft above the pivot of said links, hubs on said shaft and other links connecting said hubs and first named links, whereby rotation of said shaft will raise or lower said first named links for operating said doors.

5. In combination with a hopper car having a longitudinal V-shaped hopper on one side of the center sill and an inner door therefor hinged at its lower edge at the apex of said hopper, control means for said door comprising a longitudinal shaft, a crank arm fixed to 15 rotate with said shaft, and a link pivotally connected to said crank arm, a second link pivoted below said shaft having sliding connection with said door and a connection intermediate of its length with said first named link, said second link and door constituting a slidably connected toggle disposed and arranged so that said second link assumes a position substantially perpendicular to the plane 25 of said door when the latter is in closed position whereby to form a self-sustaining wedging prop for said door.

6. In combination with a hopper car having a longitudinal V-shaped hopper on one side of the center sill and an inner door therefor hinged at its lower edge at the apex of 35 said hopper, control means for said door comprising a longitudinal shaft, a crank arm fixed to rotate with said shaft, and a link pivotally connected to said crank arm, a second link pivoted below said shaft having 40 sliding connection with said door and a connection intermediate of its length with said first named link, said second link and door constituting a slidably connected toggle disposed and arranged so that said second link assumes a position substantially perpendicular to the plane of said door when the latter is in closed position to form a self-sustaining wedging prop for said door, said first named link being of hooked construction whereby to 45 over-lie and hang on said shaft when the door is in closed position.

7. In combination with a hopper car having a longitudinal V-shaped hopper and an inner door therefor, hinged at its lower edge at the apex of said hopper, control means for 55 said door comprising a longitudinal shaft located centrally of said car, a hub having a radially extending bearing fixed to rotate with said shaft and a hook-shaped link having 60 one end connected with said bearing, a lever pivoted below said shaft having sliding connection with said door and pivotally connected intermediate its length to the other end of said hook-shaped link, said hook-

shaped link being adapted to over-lie and hang on said hub when the hopper door is in closed position with its end bearings on opposite sides of and in alignment with the center of said shaft.

8. In combination with a hopper car having a longitudinal V-shaped hopper and an inner door therefor, hinged at its lower edge at the apex of said hopper, control means for said door comprising a longitudinal shaft 70 located centrally of said car, a hub having a radially extending bearing fixed to rotate with said shaft and a hook-shaped link having one end connected with said bearing, a lever pivoted below said shaft having sliding connection with said door pivotally connected intermediate its length to the end of said hook-shaped link, said hook-shaped link being adapted to over-lie and hang on said hub when the hopper door is in closed position with its end bearings on opposite sides of and in alignment with the center of said shaft, said lever being constructed and arranged to form a slidably connected toggle 75 with said door and to provide a perpendicularly disposed wedging prop for the upper edge of said door when the latter is in closed position.

9. In combination with a hopper car having longitudinally disposed V-shaped hoppers on opposite sides of the center sill and inner doors therefor hinged at their lower edges to the apices of said hoppers, control means for said door, comprising a pair of levers pivotally mounted between said doors 80 with their outer ends slidably connected to said doors respectively, means for oscillating said levers comprising a longitudinal shaft, cranks secured to said shaft and links connecting said cranks and levers respectively. 85

10. In combination with a hopper car having longitudinally disposed V-shaped hoppers on opposite sides of the center sill and inner doors therefor hinged at their lower edges to the apices of said hoppers, control means for said door, comprising a pair of levers pivotally mounted between said doors 90 with their outer ends slidably connected to said doors respectively, means for oscillating said levers comprising a longitudinal shaft, cranks secured to said shaft and links connecting said cranks and levers respectively, and means for imparting rotary movement to said shaft but resisting accidental rotation 100 of thereof.

11. In combination with a hopper car having longitudinally disposed V-shaped hoppers on opposite sides of the center sill and inner doors therefor hinged at their lower edges to the apices of said hoppers, control means for said door, comprising a pair of levers pivotally mounted between said doors 105 with their outer ends slidably connected to said doors respectively, means for oscillating said levers comprising a longitudinal shaft, cranks secured to said shaft and links connecting said cranks and levers respectively, and means for imparting rotary movement to said shaft but resisting accidental rotation 115 of thereof.

12. In combination with a hopper car having longitudinally disposed V-shaped hoppers on opposite sides of the center sill and inner doors therefor hinged at their lower edges to the apices of said hoppers, control means for said door, comprising a pair of levers pivotally mounted between said doors 120 with their outer ends slidably connected to said doors respectively, means for oscillating said levers comprising a longitudinal shaft, cranks secured to said shaft and links connecting said cranks and levers respectively, and means for imparting rotary movement to said shaft but resisting accidental rotation 125 of thereof.

130.

ing said levers comprising a longitudinal shaft, cranks secured to said shaft and links connecting said cranks and levers respectively, and means for rotating said shaft comprising a transverse shaft having means for manually imparting rotation thereto at its opposite ends adjacent the sides of said car and a worm and worm gear connection between said transverse and longitudinal shafts.

10 12. In combination with a hopper car having longitudinally disposed V-shaped hoppers on opposite sides of the center sill and inner doors therefor hinged at their lower edges to the apices of said hoppers, control means for said door, comprising a pair of levers pivotally mounted between said doors with their outer ends slidably connected to said doors respectively, means for oscillating said levers comprising a longitudinal shaft, cranks secured to said shaft and links connecting said cranks and levers respectively, said levers and links being longitudinally displaced with an extension 20 on the door controlled by the outermost link and lever whereby to provide a sliding connection between the said lever and door at the edge of the latter.

30 13. In a railroad car of the hopper type having longitudinal V-shaped hoppers on opposite sides of the center sill, and inside doors for said hoppers pivoted at the apices of said hoppers and adapted to open downwardly, control means for said inside doors for 35 positively and simultaneously opening and closing said inside doors.

40 14. In a railroad car of the hopper type having longitudinal V-shaped hoppers on opposite sides of the center sill, and inside and outside doors for said hoppers pivoted at the apices of said hoppers and adapted to open downwardly, control means for said outside doors and control means for positively and simultaneously opening and closing said inside doors.

45 Signed at Chicago, Illinois, this 27th day of October, 1931.

HARRY S. HART.
